BRASSIERE

Nathan Miller, Englewood, N. J.

Application May 8, 1956, Serial No. 41,396

Term of patent 14 years

(Cl. D20—4)

The sole figure shows a brassiere in dotted lines with a full line showing of an ornamental inset in the upper section respectively of the bust pockets, which full line showing constitutes the essential features of the brassiere.

I claim:

The ornamental design for a brassiere, substantially as shown and described.
